Atty.

UNITED STATES PATENT OFFICE.

ANDREW E. NELSON, OF DE KALB, ILLINOIS.

SAW-SET.

1,383,009.

Specification of Letters Patent. Patented June 28, 1921.

Application filed February 19, 1920. Serial No. 359,898.

To all whom it may concern:

Be it known that I, ANDREW E. NELSON, a citizen of the United States, residing at De Kalb, in the county of De Kalb and State 5 of Illinois, have invented certain new and useful Improvements in Saw-Sets, of which the following is a specification.

This invention relates to saw sets.

One of the objects of the invention is to 10 provide an efficient saw set.

Another object is to provide an adjustable saw set so that the teeth of the saw must be uniformly deflected from the plane of the body part thereof by operation of the 15 device.

Another object is to provide a saw set having a double, compound lever system and accurate means for adjusting the means that control the presentation of the saw to the 20 device.

Another object is to provide an adjustable gage for determining the length of the tooth to be deflected from the body part of the saw and soft renewable plates therein for contact 25 with the points of the teeth.

Other, further and more specific objects of the invention will become readily apparent to persons skilled in the art, from a consideration of the following description when 30 taken in conjunction with the drawings, wherein:—

Figure 1 is a plan view of the device.

Fig. 2 is a side elevation showing parts in sections.

Fig. 3 is an end view, and

Fig. 4 is an isometric perspective view of the gage of the device.

In all the views the same reference characters are employed to indicate similar parts.

The instrument consists of two major portions, 5 and 6, constituting the handles of the device. The part 5 is extended forwardly and the operating mechanism is mounted thereon. It is also provided with 40 upstanding ears 7 to which the handle 6 is pivoted as at 8. The forward end of the major part 5 is provided with an upstanding part 9 having a perforation 10 in which a lever 11 is pivoted, as at 12. Between an 45 overhanging portion 13, of the part 9 and the end 14 of the lever 11, is a spring 15, which maintains the front end 16 of the lever raised, and the rear end 14 depressed. The handle 6 is provided with a notch 17 50 into which the rear end 14 of the lever 11 projects, so that when the two handles 5 and

6 are brought together the front end 16 of the lever 11, is moved downwardly toward an anvil 18. The anvil 18 is tapered on its rear edge 19, to fit under an overhanging ledge 20, and a screw 21 is inserted in the front edge of the anvil 18, to hold it in place. The front end of the forward part of the member 5, is tapered, as at 22, the tapered surface being in the same plane with the front tapered surface of the anvil 18. An arm 23, having a forwardly extending portion 24, is deflected laterally to provide support for an adjustable screw 25, which is the means for determining the extent to 70 which the teeth of the saw are to be deflected by operation of the lever 11. The arm 23 is provided with a slot 26 and it is fixed in a groove 23' made in the upstanding portion 9. A tooth gage 27 is provided with 75 an elongated slot 28 and is adjustably secured to the underside of the front end of the member 5, by a screw 29. It is also provided with upstanding arms 30 and 31, and these arms are arranged to contain removable soft metal blades 32, preferably made of copper, or other soft metal, for contact with the points of the teeth of the saw. The copper part, 32, extends through slots 80 provided in the upper and lower ends of the 85 upstanding members 31, and are replaceable. The object of making the part 32 of soft metal is, to not injure the points of the teeth as the saw is being set. The gage 27 may be moved forwardly or rearwardly 90 to regulate the length of the tooth to be deflected by the operation of the device.

The operation of the device is as follows:—

The tooth edge of the saw is presented to 95 the set and the screw 25 is positioned to determine the extent to which the tooth is to be deflected from a plane through the main body part of the saw. The higher the end of the screw 25 is located with reference to 100 the surface 22, the less will be the depression of the tooth, and the lower the end of the screw 25, the greater will be the depression.

The saw is presented between the surface 22 and the lower end of the screw 25, and the end 16 of the lever 11 engages the tooth and deflects it out of the plane of the surface 22 into a substantially horizontal plane. The gage 27 determines the distance that the teeth may be moved from the lower end of 110 the screw 25 on to the anvil 18. The arm 23 may be adjusted axially of the device, by

loosening the screw 33, and after the screw 25 has thus been located in the proper position, the screw 33 is again tightened.

After a tooth has been deflected, the device 5 is moved along the tooth edge of the saw deflecting alternate teeth, after which the saw is reversed and the intermediate teeth are deflected in the same manner, as usual in devices of this character.

10 It will be observed that every feature of the device is adjustable so that great accuracy may be obtained in the work performed by its use.

While I have herein shown a single embodiment of my invention for the purpose of clear disclosure, it will be manifest to persons skilled in the art, that many changes may be made in configuration and disposition of the parts within the scope of the 20 appended claims.

Having described my invention, what I claim as new and desire to secure by Letters Patent is:—

1. A saw set having a major portion providing a handle at one end and having a vertically upstanding part at the other end, the latter end being tapered to receive the flat surface of a saw; a short lever pivoted in the upstanding part and having its front 30 end tapered to engage the teeth of a saw; a

handle pivoted to the major portion of the device having a short end engaging the rear end of the short lever and a spring engaging the upstanding part and the rear end of the short lever to yieldingly hold the front end 35 of the short lever normally elevated.

2. A saw set providing a gage for determining the location of the bend in saw teeth, said gage having replaceable plates for contact with the points of the saw teeth, in combination with a vertically adjustable means for determining the extent of the bend and longitudinally adjustable means to change the position of the vertically adjustable means. 40

3. A saw set having a member provided with a tapered front end; a replaceable insert anvil in said end, continuing the taper, said anvil having a horizontal surface joining the tapered surface; a lever having an 50 end overlying said horizontal surface; a spring to normally hold said end elevated; a handle to depress said end; a screw in front of said lever adjustable vertically and means whereby said screw may be adjusted 55 longitudinally of the device.

In testimony whereof I hereunto subscribe my name.

ANDREW E. NELSON.
